AUTOMATIC CONTAINER FILLING
DEVICEEdwin F. Hulbert, Glenview, Ill., assignor to
Anacin Company, Chicago, Ill., a corporation
of Delaware

Application October 26, 1931, Serial No. 571,131

78 Claims. (Cl. 93—6)

The present invention relates to automatic machines or devices, and more particularly to a novel automatic operating machine for filling a container, box, package and the like, with a quantity 5 of material, such as a plurality of pills, tablets, or the like.

Among the objects of the present invention is to provide a novel machine having automatically operated means for transferring a quantity of 10 material from a source of supply and depositing the same in a container in which the same is offered for sale.

Another object of the present invention is to provide a novel automatic machine, including 15 means intermittently moved, for positioning empty containers or the like at intervals in a given location, at which point novel means is provided for depositing material, such as a plurality of tablets, or the like, therein.

20 The invention further comprehends the idea of providing novel means for wrapping a given quantity of material during the transfer thereof from a source of supply to an empty container, such means including means associated with the 25 transfer means for properly positioning the wrapping material, whereby the material is evenly and uniformly wrapped when deposited in the empty container.

Still another object of the invention is to provide 30 means, in an automatic machine for filling empty containers, for closing these containers when filled so that the same are in condition to be packed for shipment.

A further object of the invention is to provide 35 a novel automatic machine having means for transfer of a quantity of material from a source of supply and for depositing the same in an empty container, this machine further including means operated to deposit a filler in the container and 40 in association with the material to prevent damage thereof after the same has been packed, and during shipment. This filler serves the dual function of not only preventing damage to the material, but likewise includes printed matter for instructing the consumer as to the proper use of 45 the material.

The invention further contemplates the idea of providing means, in an automatic machine for filling empty containers, for cutting or severing 50 wrapping portions from a roll of wrapping material at the proper interval and in a position immediately adjacent the material being transferred to the containers. Further means is provided and is associated with this cutting means 55 for positioning this wrapping portion in contigu-

ous relation with the transferred material and at the proper interval of time.

Still another object of the invention is to provide an automatic container filling machine having or including means for transferring material 5 at intervals from a source of supply to empty containers and having means associated therewith for picking up this material from the source of supply and depositing the same in the empty container.

In an embodiment selected to illustrate the invention such means comprises a cross-head for transfer of the material to the container, this cross-head having suction means associated therewith for lifting the material from the source 15 of supply, means being further provided for breaking or releasing this suction when the transferred material is in a position above the containers, whereby the same is properly deposited in the containers.

A still further object of the invention is to provide an automatic container filling device having means for wrapping a quantity of material during the transfer thereof from a source of supply to a container, such wrapping means including suction means for properly positioning a 25 wrapping portion of material in contiguous relation with the material.

Still another object of the invention is to provide a novel automatic container filling machine 30 having a power driven conveyor adapted to be intermittently moved for positioning empty containers at intervals of time in a given position to be filled, means being further provided and operated by the drive means for the conveyor to 35 close the containers at the proper interval.

Still further, means is provided and operated by the drive means for the conveyor for discharging the containers when filled from the conveyor and onto suitable means for transferring the 40 same to a place where they can be packed for shipment.

Other objects, capabilities, advantages and features are comprehended by the invention, as will later appear and as are inherently possessed 45 thereby.

Referring now to the drawings:

Figure 1 is a side view in elevation of a machine made in accordance with the present invention;

Figure 2 is a fragmentary top plan view of 50 the embodiment disclosed in Figure 1 of the drawings;

Figure 3 is a fragmentary vertical cross-sectional view taken in a plane represented by line 55 3—3 of Figure 2 of the drawings;

Figure 4 is a fragmentary vertical cross-sectional view taken in the planes represented by the line 4-4 of Figure 2 of the drawings;

Figure 5 is a transverse vertical cross-sectional view taken on the line 5-5 of Figure 2 of the drawings;

Figure 11 is a fragmentary view in end elevation of the wrapping and cutting means with parts broken away to disclose more in detail the means for supplying the wrapping material;

Figure 12 is a fragmentary vertical cross-sectional view of the wrapping and cutting mechanism of the present device and is taken in a plane represented by line 12-12 of Figure 2 of the drawings;

Figure 13 is a fragmentary vertical cross-sectional view taken in a plane represented by line 13-13 of Figure 12 of the drawings;

Figure 14 is a fragmentary vertical cross-sectional view taken in a plane represented by line 14-14 of Figure 13 of the drawings;

Figure 15 is a view in perspective disclosing in detail the construction of the lifting means for reciprocating the transfer means of the present embodiment;

Figure 16 is a broken view in perspective of the cam means for operating the lifting means disclosed in Figure 15 of the drawings; and

Figure 17 is a fragmentary top plan view of the conveying means of the present device and having parts broken away to disclose in detail the means for closing the containers and discharging the same from the conveyor.

Referring now more in detail to the drawings, an embodiment selected to disclose the present invention is shown as comprising a conveying means, generally designated as 2, for conveying empty containers or boxes 4 at intervals to a given point where the same are filled by a material transfer means, generally referred to as 6, for transferring a quantity of material, such as a plurality of pills, tablets, or the like 8, from a source of supply, generally referred to as 10.

These tablets 8 are emptied into a bin or funnel 12 secured, as by the bolts 14, to a bracket 16 connected to upstanding lugs 17 of a shelf or platform 19 of an elongated bracket 20 attached as by means of bolts 22 to the main frame of the machine, a second bin or container 18 being supported upon the platform 19 and directly beneath the funnel 12. The pills 8 are adapted to pass down through an opening in the container 12 and into the second container 18, this second

container 18 being provided with a plurality of channels 24 formed in the base plate 26, these channels converging toward the machine and communicating with channels 28 formed in a chute 29. As clearly shown in Figure 3 of the drawings, the channels 24 in the container 18 are adapted to receive the pills or tablets 8 in an endwise direction, the channels 28 in the chute 29, however, being formed, as clearly indicated in Figures 2 and 3, with a twist 30 so as to rotate these pills through an arc of 90 degrees to position the same in the channels 28 on their flat sides.

An end of the container 18 is pivoted, as at 32, to the lugs 17 and is supported at its opposite end upon a transverse eccentric rod 34 journaled in suitable bearings in a casting 35 of the chute 29 which rests on the shelf 19, this rod having a gear 36 secured thereto on one of its ends which meshes with a pinion 38 mounted upon the drive shaft of an electric motor 40. It will be clearly understood, that as the eccentric shaft 34 is rotated by the motor 40, the container 18 is vigorously oscillated about the pivot points 32 so as to stir up and agitate the tablets 8 within the container and for positioning these tablets in the channels 24, the same being urged downwardly by this movement toward the passages 28 in the chute 29. The speed of rotation of the drive shaft of the motor 40 is controlled through a rheostat 42.

In the present embodiment, the material supplying means 10 is disclosed as having four channels or passages 28 in the chute 29 which communicate with an opening 44 in a casting 46 of the main frame of the device, these tablets being adapted to be urged by gravity onto a plate 48 of a material lifting means 50 (to be later more fully disclosed), the opening 44 being of such a width as to permit a series of three units of these tablets to be positioned on the plate 48 at any given time.

The various mechanisms of the present machine, such as the rotating conveyor 2, the transfer means 6, as well as means for cutting wrapping portions of material and wrapping the tablets with this material, generally designated as 52, and various other mechanisms are driven and operated by a single drive means. Such drive means comprise an electric motor 54 secured in any suitable manner to a bracket 56 bolted, as by means of the bolts 58, to the main machine casting 60 having a base 62 for supporting the device on any suitable foundation. This electric motor 54 drives a belt 64 through a pulley 66, this belt passing over a pulley 68 keyed to a shaft 70 mounted for rotation within a housing comprising an upper casting 72 and lower casting 74 connected together by any suitable means, such as bolts 76. This upper casting 72 is connected by means of the bolts 78 to the upright standard 80 of the casting 60, while the lower casting 74 is secured and maintained in position through the medium of the bolts 76. Mounted upon the shaft 70 is a worm 84 meshing with a gear 86 connected, as by means of the bolts 88, to a sleeve 90 mounted for rotation about a hollow shaft 92 having shoulder portions 94 seating on the upper surface of a bracket 96, the lower end of this hollow shaft 92 being threaded and secured to the bracket 96 as by means of the lock nut 98. The bracket 96 is connected by means of the bolts 100 to the lower central portion of the standard 80 of the main casting. The rotatable sleeve 90 has its lower end rest-

70
75
80
85
90
95
100

ing upon a washer 102 on the bracket 96, while its upper end is provided with spaced clutch elements 104 adapted to engage with similar clutch elements on the lower end of another sleeve 106

5 mounted within a bushing 108 fitting within an opening in the upper casting 72. The upper end of the sleeve 106 is formed with gear teeth 110 meshing with the gear teeth of a gear 112 keyed to a shaft (not disclosed), suitably journaled in 10 an enlarged circular bearing portion 114 of the upper casting 72. Means (to be later more fully disclosed), is associated with the gear 112 for intermittently rotating the conveyor 2.

The sleeve 90 is provided with a notch or cam slot 116 adapted to provide a cam surface for the travel of a roll 118 mounted upon a square shaft 120 adapted to reciprocate within a bushing or sleeve 121 mounted in the bracket 96. A cross-head 122 is provided with an opening fitting over 20 a small shoulder portion 124 of the shaft 120 and is secured thereto by means of a nut 126 threadedly engaging the small end 124 of the shaft. The outer end of this cross-head 122 is apertured to receive the shouldered end 128 of 25 a control rod 130 and is secured thereto by a nut 132 threadedly engaging the rod portion 128. This control rod 130 is mounted for reciprocating movement in the lower end 134 of the hollow shaft 92 and extends upwardly and above the 30 transfer means 6 and has a cross-head 136 secured thereto, as by means of a bolt 138. This cross-head 136 is for the purpose of controlling the operation of various mechanisms of the device and the same will be hereinafter more fully 35 described in conjunction with these various mechanisms.

The conveyor means 2 comprises a hub 140 having an upper disc portion 142, a lower disc portion 144 and an intermediate disc portion 146 40 extending laterally of the hub, this hub being mounted for rotation about the vertical shaft 148 fixed in a bearing 150 provided in the upper part of the standard 80, the lower end of this shaft 148 being secured in place by the bolt 152.

45 The upper disc 142 is formed with a peripheral shelf portion 156, a plurality of spaced depressions 158 being provided therein and adjacent the periphery thereof. An operator standing approximately at the point A adjacent the machine places a container in each of the depressions 158 when the same come within reach, each of the containers 4 having a cover 160 which at that time is moved rearwardly into abutting relation with an upper or top disc or plate 154 fixedly 50 mounted on the upper end of the shaft 148.

55 In the present embodiment, these containers 4 are disclosed as being made of metal, and in order to hold the same in place within the depressions 158, an electromagnet 162 is provided immediately adjacent and beneath each and every depression. These electromagnetic devices are each provided with a pole 164 having a head 166 seating within a recess provided in the depression 158, this pole extending downwardly 60 through an opening in the disc and having a nut 168 threaded onto the lower end thereof for holding the magnetic devices in position and in contact with the lower surface of the disc 142. These electromagnetic devices effectively hold 65 each of the containers 4 in position within a depression during the entire travel of the same from a point immediately adjacent the area marked A until discharged from the conveyor. Each of these electromagnetic devices 162 are in an electric circuit 168a terminating in the collector rings

170 mounted on the lower portion of the hub 140 and contacting with terminals or brushes (not disclosed) of an electric circuit supplying current thereto.

The conveyor 2 is intermittently moved by means of an annular disc member 172 secured as by means of the bolts 174 to the lower disc 144. This annular disc member 172 is provided with spaced slots 176 provided on the periphery thereof and extending inwardly and radially toward 10 the axis of the shaft 148. These slots are suitably spaced so as to be engaged by a roll 178 mounted in off-center relation to the gear 112. It will be clearly understood that as the gear 112 is rotated through the gear 110 and sleeve 106, the 15 roll 178 will progressively engage successive slots 176 of the disc 172 for intermittently moving the same. Arcuate shaped recesses 180 are provided on the periphery of the annular disc member 172 and intermediate adjacent slots 176, these arcuate shaped recesses being adapted to engage with a corresponding arcuate surface 182 of a member mounted upon the gear 112 for holding the annular disc member 172 in a stationary position 20 during the interval between the disengagement 25 of the roll 178 from one slot and its engagement with a successive adjacent slot. This mechanism is effective in producing a uniform intermittent movement for successively positioning an open container 4 directly opposite and in spaced relation with the platform 48 of the material lifting means 50.

The upper or top disc or plate 154 fixed to the shaft 148 is provided with a central cam slot 184 adapted to receive rolls 186 mounted on a plurality of T-shaped push-rods 188 mounted in slots 190 in the disc or plate member 142, these rods 188 extending toward and terminating inwardly, when in an inoperative position, of the depressions 158. The cam groove 184 is so constructed 40 as to position these rods 188 within the disc 154 during a greater portion of the travel of any given point of the periphery of the disc 142. These rods 188 are adapted to move outwardly, however, after the container 4 has been filled with the 45 tablets for engagement with the cover 160 so as to close the same. The boxes are normally retained from moving outwardly and radially in the depressions 158 by means of a peripheral band 191 secured as by means of brackets 192 to the 50 disc 154. This peripheral band 191, however, has a lower portion 194 adjacent a discharge platform 196 so that when each of the containers 4 has been filled with tablets, and the rod or arm 188 associated therewith is operated through the medium of the cam slot to close the box, then the same may move outwardly and radially relative to the depressions and be deposited on the discharge shelf 196, this discharging being effected by further outward movement of the arm 188. 60 This discharge platform 196 overlaps a continuously operated conveyor belt 198 operated through a chain drive 200, a reducing gear 202 and a belt 204 driven through a pulley 206 keyed to the shaft 70, this conveyor 198 being adapted to discharge the filled containers 4 to a point remote 65 from the machine for packing the same for shipment.

The transfer means of the present device for 70 transfer of a set of 12 tablets from the lifter plate 48 and for depositing the same in an open container directly opposite thereto, comprises a cross-head 208 formed in the shape of a cross having a hub 210 mounted upon a sleeve 212 which in turn is slidably mounted upon the upper end of 75

the hollow shaft 92. The cross-head 208 is provided with outwardly extending arm portions 214 spaced apart at 90 degrees and having head portions 216, 218, 220 and 222 for picking up sets of 5 pills or tablets and depositing the same at the proper interval of time into an open container.

This cross-head 208 has both movement of rotation and movement of translation in an up and down direction over the hollow sleeve 92. The reciprocal movement of translation is effected by means of cam pieces 224 secured to the upper 10 end of the sleeve 106 and adapted to be continuously operated thereby when the machine is in operation. These cam pieces 224 are adapted to intermittently contact with a case hardened lug 226 secured to the lower surface of a cross-head lifter 228 mounted about the hollow sleeve 92, the lower end of the sleeve 212 normally resting or bearing upon the upper surface of this 15 lifter. This lifter member 228 is provided with a bifurcated arm 230 guided by means of an upright rectangular lug 232 formed on the U-shaped channel 234 of the casting 46.

A second cam piece 234 is secured to the upper 20 end of the sleeve 106 and extends outwardly directly beneath the lower end of a rod 236 of the material lifting means 50, this rod 236 being mounted for movement within guiding surfaces of the casting 46. The rod 236 is provided with 25 a lug 238 engaged by the end of a coil spring 240 tending to urge the rod 236 downwardly, whereby the upper surface of the plate 48 is beneath the tablet supply channels or grooves 28 provided in the chute 29, the downward movement of the rod 30 236 being controlled by engagement of the lug 238 with a shelf 242 on the casting 46.

Movement of rotation of the cross-head 208 is effected by means of a ring gear 244 mounted on the lower part of the sleeve 212 which is adapted 35 to engage with gear teeth 246 on the intermediate disc 146 of the conveyor. The teeth of the gear 244 and teeth 246 intermesh for intermittently rotating the cross-head 208 through an arc of 90 degrees when the conveying means 2 is intermittently rotated through the mechanism controlled by the operation of the roll 178. The movement of translation of this cross-head 208 in an up and down direction takes place during 40 the interval of time that the conveyor means 2 is stationary so that there is no clashing of the teeth of the gear 244 and the teeth 246 of the conveyor means.

Upon the downward stroke of the cross-head 208, one of the heads thereof is adapted to be positioned 45 immediately above the material lifter plate 48, while an opposite head thereof is adapted to be positioned immediately above an empty container 4 on the conveying means 2. At this time, a set of tablets is adapted to be picked up by the head 50 immediately thereabove and a set of tablets deposited from the opposite head into the empty container directly beneath the same.

This picking up and depositing is effected 55 through the medium of suction suitably controlled for effecting these results. Each of the heads is provided with a laterally extending duct or conduit 248, communicating with the annular passage 250 between the shaft 130 and sleeve 92, the lower end of this annular passage 250 communicating 60 with an outlet duct 252 connected to suitable means for creating a suction therein. Each of the heads of the cross-head 208 is provided with a vertically disposed bore 253 having a bushing 254 fitting therein for receiving a control push rod 256 having a recessed portion 258

in its lower end against which seats a coil spring 260 having its other end resting upon a head plate 262 provided with perforations 264 so positioned as to be centrally located relative to the tablets on the plate 48, these perforations 264 terminating in arcuate depressions 266 conforming substantially to the contour of the side surface of the tablets. Each of the heads of the cross-head is provided with a port 268 normally closed by the lower end of the push rod 256 when the same is 10 directly above the plate 48 of the material lifter. At this time, the port 270 of the channel 248 is open to permit the suction to act through the perforations 264 for drawing or picking up the tablets from the plate 48. At this particular 15 moment, the cam piece 234 is in a position to engage with the lower end of the rod 236 for raising a set of tablets upwardly toward the cross-head directly thereabove and for cutting off the supply of tablets moving downwardly in the channels or 20 grooves 28. This suction is of sufficient strength to maintain these pills within the depressions 266 of the head plate 262 until such time as this head has been intermittently rotated into a position 25 above an empty container on the conveying means 2. It is of course understood that upon upward movement of the plate 48 the cross-head 208, because of the disengagement of cam pieces 224 with the lug 226, is in its lowermost position.

Each of the heads of the cross-head is provided with an ear 271 to which is pivotally connected a plate 272 having an aperture 274 surrounding the rod 256, this plate normally being moved into angular and binding relation with the rod 256 by means of a coil spring 276 within a 30 cap 278 fitting over a lug 280 screwed into the cross-head arm 210.

When a head of the cross-head 208 is above the plate 48, the upper cross-head 136 is moved downwardly by means of the cam roller 118 operating 40 in the cam slot 116 to a point where the downwardly disposed bolt 282 carried thereby engages with the plate 272 to release the rod 256, which, under the influence of the coil spring 260, moves upwardly for opening the port 270, this 45 upward movement being controlled by the stop bolt 284 similarly carried in the cross-head 136.

Simultaneously with this downward movement of the cross-head 136 for operation of the rod 256, a bolt 286 carried in an opposite arm of 50 the same, comes into engaging relation with the rod 256 of the head of the cross-head directly above the empty container. This bolt 286 causes a downward movement of the rod 256, whereby the lower end of the rod 256 closes the port 55 270 leading to the suction duct 250 and opens, by means of a passage 288, the port 268, thereby breaking the suction to release the tablets for depositing the same in the container 4. The coil spring 276 immediately acts to cause a 60 binding between the plate 272 and rod 256 to hold the rod 256 in this position until this head of cross-head has been moved into a position above the plate 48.

In order to properly wrap these tablets, wrapping means is comprehended by the present invention and includes means for severing a wrapping portion of the wrapping material and wrapping the tablets with this wrapping portion. The wrapping material is supplied in the form 70 of a roll 290 supported in a bracket 292 connected, as by means of bolts or the like 294, to the upper casting 72. A brake mechanism comprising an arm 291 having a block 293 adapted to contact with the roll 290, is pivotally sup- 75

ported by an arm 295 connected to the bracket 292 and has a weight 297 secured to its lower end tending to maintain the block 293 in contact with the roll 290 to provide uniform movement of the same upon the unwinding of the wrapping material.

The free end of this wrapping material extends upwardly and between two rolls 296 and 298 mounted upon the shafts 300 and 302, respectively, these shafts being suitably journaled in the side walls of a housing 304. These rolls are suitably driven by means of a gear 306 meshing with the gear 244 on the sleeve 212, this gear being mounted on a shaft 308 journaled in the housing 304 and provided with another gear 310 secured to the shaft and meshing with a gear 312 mounted upon a shaft 314. This shaft 314 is mounted for rotation in the housing 304 and is provided with a second gear 316 secured to an end thereof which in turn is adapted to mesh with a drive gear 318 secured to an end of the shaft 302 and for driving the same. This gear 318 is still further in meshing relation with another gear 320 mounted on the shaft 300 for simultaneous movement of rotation of the roll 296 with the roll 298.

Means for adjusting the bite between the rolls 296 and 298 comprises a thumb nut 374 having a shank threaded in a plate 376 having bolts 378 secured thereto adjacent its end, these bolts 378 being adapted to pass downwardly through enlarged openings provided in a top plate 380 for the casting 304 and engage with bushings 382 mounted in the walls of the casting 304. Coil springs 384 are interposed between the top plate 380 and these bushings 382 and about the bolts 378 for urging these bushings 382 downwardly in the openings provided in the walls of housing 304. It will be seen that movement of the thumb screw 374 in an upward direction will decrease the distance between the plate 376 and top plate 380 thereby permitting the springs 384 to exert a force against the bushings 382 and for tightening the bite between the rolls 296 and 298.

The free end 322 of the wrapping material extends through the bite between the upper and lower feeding rolls 296 and 298 and protrudes through an opening 324 in the housing 304 and directly above a shelf portion 326. The housing 304 is formed with a downwardly extending ledge portion 328 above the opening 324 and has secured thereto a block 330 as by means of the bolt 332, this bolt 332 extending through an elongated opening or slot 334 in the block 330, whereby the block may be moved or adjusted. This block 330 is tightened by means of set screws 336 adapted to have their ends in abutting relation with the downwardly extending ledge portion 328, this block 330 having a knife element 338 secured along the lower edge thereof. The platform or shelf 326 of the casting has a depression 340 formed therein adapted to receive a cross piece 342 of a movable element 344 pivoted as by means of a shaft 346 to an ear or lug 348 integral with the shelf 326. The cross member 342 is made integral with sector portions 350 of the movable element 344 and has a knife element 352 secured to its upper surface for cooperation with the knife element 338 for cutting or severing a wrapping portion from the free end 322 of the wrapping material.

The movable element 344 is raised and lowered by means of a vertical rod 354 controlled ex-

tending downwardly from an outwardly extending arm 358 of the upper cross-head 136. This rod 354 is provided with gear teeth 360 meshing with gear teeth 362 on one end of a rod 364 journaled in the housing 304. The teeth 362 are of such a length as to have a portion thereof meshing with teeth provided on one of the sectors 350 on one side of the shelf 326, while another portion at the other end of the shaft 364 is provided with teeth 366 engaging the teeth of another sector portion positioned on the other side of the shelf 326.

When a head of the cross-head 208 has picked up a set of tablets from the plate 48 and has been rotated into a position adjacent the wrapping means 52, these tablets are in a position relative to the free end 322 of the wrapping material, as clearly shown in Figure 13 of the drawings. At this particular instant of time the cross-head 136 moves downwardly whereby the bolt 356 contacts with the rod 354 to cause an upward movement of the sectors 350 and for raising the cross member 342, whereby the knife element 352 cooperates with the knife element 338 to sever a wrapping portion from the roll 25 of wrapping material. This upward movement of the cross member 342 raises this wrapping portion of material up into contiguous relation with the set of pills carried by this cross-head and the same is maintained in that position by the sucti- 30 tion created in the head of the cross-head.

As clearly shown in Figure 11 of the drawings, a part of this wrapping portion is moved upwardly by the cross member 342 into a position sufficiently close to a port 368 provided in the outer part of each of the heads of the cross-head, whereby the outer end of this wrapping portion is drawn into a substantially vertical position. This outer part of the wrapping portion of material is started in its upward movement by 40 means of a latch member 370 pivoted to the housing 304 and supported thereby adjacent and above the knife element 352. Upon upward movement of this knife element 352 the same contacts with the latch member 370 and to raise 45 the same into a position, as shown in dotted lines in Figure 12 of the drawings. Movement of this latch member 370 is controlled by a bracket 372 projecting above and inwardly of the point of pivotal support of the same.

The movable member 344 is returned into a position wherein the cross member 342 is positioned in the slot or groove 340 under the action of a coil spring 361 interposed between a plate 363 connected to the housing and the end of the rod 354. This coil spring 361 not only returns the movable member 344 into its lowered position, but also returns the rod 354 into its uppermost position for engagement with the bolt 356 upon the next successive downward movement of the cross head 136 for severing a wrapping portion of material for the next successive set of tablets carried by the adjacent head of the cross-head 208.

The invention further contemplates the idea of providing suitable mechanism adapted to deposit or insert a filler into the empty containers at the proper interval this filler material serving a dual purpose, namely, to fill the space between the tablets and the walls of the container 70 when the same has been filled with material, and to serve as an instruction sheet for the consumer as to the proper use of the material or tablets packed within the container. These fillers are shown as comprising folded pieces of paper 386, 75

packed together adjacent one another in an elongated U-shaped channel 388 supported upon blocks or supports 390, this channel being secured by any suitable means to the top disc member 154 in such a position that its inner open end is adjacent and directly above the cover 160 of a container 4 directly opposite the platform 48 of the material supply means. These fillers are normally urged toward this inner open end 10 by means of a follower block 392 having trunnions 394 operating and movable in slots 396 provided in the side walls of the U-shaped channel 388. Each of the trunnions 394 is provided with an aperture or opening through which a cord 398 passes and which is knotted for anchoring the same thereto. This cord 398 passes over a pulley 400 at the inner open end of the channel 388 and extends rearwardly over another pulley 402 at the outer open end of the channel and 20 downwardly and has a weight 404 connected to the end thereof. These weights 404 tend to urge the follower block 392 inwardly so as to maintain the fillers 386 in close relation whereby each of the fillers is in a position to be positively fed 25 or deposited into the containers.

At the interval of time during the downward movement of the cross-head 136 when the bolt 286 contacts with a rod 256 for breaking the suction of a head of the cross-head 208 directly 30 above an empty container, the blade 406 secured to a cross member 408 connected to a bolt 410 on the cross head 136, likewise moves downwardly and the curved or flanged end 412 thereof engages with a filler which has been forced downwardly under the action of a prong 413, as clearly shown in Figure 6 of the drawings, to deposit the same in the cover 160 of the container being filled with a series of tablets. This blade 406 further functions to provide an abutment for 40 holding the fillers 386 within the channel 388. A strap or retaining member 414 is secured to the upper edges of the channel 388 and adjacent the inner open end thereof for preventing upward movement of the fillers 386. During the 45 up and down movement of translation of the cross-head 136, the same is guided by guide rods 420 connected in any suitable means to the cross member 408 and movable within openings provided in the guide blocks 422 secured as by 50 means of the bolts 424 to the top disc member 154.

After a container has been supplied with a filler, as described above, the same is intermittently moved on the rotating conveyor 2 in a direction toward the discharge plate 196. During this movement toward the discharge plate 196, the arm 188 associated therewith is moved in the cam slot 184 so that its outer end moves against the cover 160 to close the same. At the 55 instant of time after this cover 160 has been moved into a closed position, a bolt 426 connected to an arm 428 of the cross-head 136 moves downwardly therewith to engage the top 160 and to cause an engagement of snaps 430 provided 60 on both the bottom and top of each of the containers. Upon further outward movement of the rod 188, the closed and filled container is discharged upon the discharge plate 196 and is then 65 conveyed along the endless belt 198 to a place 70 where the same is packed for shipment.

While I have herein described and upon the drawings shown an illustrated embodiment of the invention, it is to be understood that the invention is not limited thereto but may comprehend other constructions, arrangements of parts,

details and features without departing from the spirit thereof.

Having thus disclosed the invention, I claim:

1. An automatic container filling machine, comprising means for conveying an open container to a given point to be filled, means for supplying material for said container, means for picking up said material, means for bringing a wrapping portion into association with said material, and means for depositing said material with a wrapping portion in association therewith in said container. 5

2. An automatic container filling machine, comprising means for conveying an open container to a given point to be filled, means for supplying material for said container, means for picking up said material, means for bringing a wrapping portion into association with said material, means for depositing said material with a wrapping portion in association therewith in 10 said container, and means for closing said container. 15

3. An automatic container filling machine, comprising means for conveying an open container to a given point to be filled, means for supplying material for said container, means for placing a wrapping portion in position to be transferred into association with said material, means for transferring said portion into association with said material, means for depositing said material 25 with said wrapping portion in said container, and means for depositing a loose filler in said container and for moving the same into a position immediately above said material to prevent damage of said material when packed. 30

4. An automatic container filling machine, comprising means for conveying an open container having a hinged cover to a given point to be filled, means for supplying material for said container, means for placing a wrapping portion in 40 position to be transferred into association with said material, means for transferring said portion into association with said material, means for depositing said material with said wrapping portion in said container, means for depositing a loose filler in said container adjacent said cover to prevent damage of said material when packed, and means for closing the cover of said container and to move said loose filler into a position immediately above said material. 45

5. An automatic container filling machine, comprising means for conveying an open container having a hinged cover to a given point to be filled, means for placing a wrapping portion in 55 position to be transferred into association with a quantity of material, means for transferring said portion into association with said material, means for depositing said material with said wrapping portion in said container, means for depositing a loose filler in said container adjacent said cover to prevent damage of said material when packed, and means for closing said container and to move said loose filler into a position 60 immediately above said material. 65

6. An automatic container filling machine, comprising means for conveying an open container having a hinged cover to a given point to be filled, means for depositing material with a wrapping portion associated therewith in said container, means for depositing a loose filler in said container adjacent said cover to prevent damage of said material when packed, and means for closing said container and to move said loose 70

filler into a position immediately above said material.

7. An automatic container filling machine comprising means for conveying an open container to a given point to be filled, means for supplying material for said container, means for picking up said material, means for bringing a wrapping portion into association with said material, means for depositing said material with its associated wrapping portion in said container, and means for depositing a filler in said container to prevent damage to said material when packed.

8. An automatic container filling machine, comprising means for conveying an open container to a given point to be filled, means for supplying material for said container, means for picking up said material, means for bringing a wrapping portion into association with said material, means for depositing said material with its associated wrapping portion in said container, means for depositing a filler in said container to prevent damage to said material when packed, and means for closing said container.

9. An automatic container filling machine, comprising means for conveying an open container to a given point to be filled, means for supplying material for said container, means for picking up said material, means for bringing a wrapping portion into association with said material, means for depositing said material with its associated wrapping portion in said container, means for depositing a filler in said container to prevent damage to said material when packed, means for closing said container, and means for conveying said closed container to a point for packing.

10. An automatic container filling machine, comprising means for conveying an open container to a given point to be filled, means for supplying material for said container, fluid means for picking up said material, means for bringing a wrapping portion into association with said material, and means for depositing said material with its associated wrapping portion in said container.

11. An automatic container filling machine, comprising means for conveying an open container to a given point to be filled, means for supplying material for said container, fluid means for picking up said material, means for bringing a wrapping portion into association with said material, means for depositing said material with its associated wrapping portion in said container, and means for closing said container.

12. An automatic container filling machine, comprising means for conveying an open container to a given point to be filled, means for supplying material for said container, fluid means for picking up said material, means for bringing a wrapping portion into association with said material, means for depositing said material with its associated wrapping portion in said container, and means for depositing a filler in said container to prevent damage to said material when packed.

13. An automatic container filling machine, comprising means for conveying an open container to a given point to be filled, means for supplying material for said container, fluid means for picking up said material, means for bringing a wrapping portion into association with said material, means for depositing said material with its associated wrapping portion in said container, means for depositing a filler in said container to

prevent damage to said material when packed, and means for closing said container.

14. An automatic container filling machine, comprising means for conveying open containers at intervals to a given point to be filled, means for supplying material for said containers, means for picking up a quantity of material from said supply, means for simultaneously bringing a wrapping portion into association with a previously picked up quantity of material, and means for simultaneously depositing a previously picked up quantity of material in a container.

15. An automatic container filling machine, comprising means for conveying open containers at intervals to a given point to be filled, means for supplying material for said containers, means for transferring a quantity of said material to a container, said means including suction means for picking up said quantity of material from said supply, means for breaking said suction for depositing said material in a container, and means for bringing a wrapping portion into association with said material during said transfer.

16. An automatic container filling machine, comprising means for conveying open containers at intervals to a given point to be filled, means for supplying material for said containers, means for transferring a quantity of said material to a container, said means including suction means for picking up said quantity of material from said supply, means for breaking said suction for depositing said material in a container, and means for bringing a wrapping portion into association with said material during said transfer, said means including said suction for positioning the wrapping material.

17. An automatic container filling machine, comprising means for conveying open containers at intervals to a given point to be filled, means for supplying material for said containers, means for transferring a quantity of said material to a container, said means including suction means for picking up said quantity of material from said supply, means for breaking said suction for depositing said material in a container, means for supplying a wrapper for said material and during said transfer, and means for picking up said wrapper into contiguous relation with said material, said last mentioned means including said suction.

18. An automatic container filling machine, comprising means for conveying open containers at intervals to a given point to be filled, means for supplying material for said containers, means for transferring a quantity of said material to a container, said means including suction means for picking up said quantity of material from said supply, means for breaking said suction for depositing said material in a container, means for supporting wrapping material, means for feeding said wrapping material adjacent said picked up material, means for severing a wrapping portion, and means for picking up said wrapping portion into contiguous relation with said material, said last mentioned means including said suction.

19. An automatic container filling machine, comprising means for conveying open containers at intervals to a given point to be filled, means for supplying material for said containers, an intermittent reciprocating and rotating cross-head for transfer of said material from said supply to a container, suction means cooperating with said cross-head for picking a quantity of material up from said supply, means for placing

- a wrapping portion in association with said material, and means for breaking said suction for deposit of said material together with said wrapping portion in a container.
- 5 20. An automatic container filling machine, comprising means for conveying open containers at intervals to a given point to be filled, means for supplying material for said containers, an intermittent reciprocating and rotating cross-head for transfer of said material from said supply to a container, suction means cooperating with said cross-head for picking a quantity of material up from said supply, means for breaking said suction for deposit of the same in a container, and means for bringing a wrapping portion into association with said material during said transfer.
- 10 21. An automatic container filling machine, comprising means for conveying open containers at intervals to a given point to be filled, means for supplying material for said containers, an intermittent reciprocating and rotating cross-head for transfer of said material from said supply to a container, suction means cooperating with said cross-head for picking a quantity of material up from said supply, means for placing a wrapping portion in association with said material, means for breaking said suction for deposit of said material together with said wrapping portion in a container, and means for deposition of a filler in said container to prevent damage of said material when packed.
- 15 22. An automatic container filling machine, comprising means for conveying open containers at intervals to a given point to be filled, means for supplying material for said containers, an intermittent reciprocating and rotating cross-head for transfer of said material from said supply to a container, suction means cooperating with said cross-head for picking a quantity of material up from said supply, means for breaking said suction for deposit of the same in a container, means for bringing a wrapping portion into association with said material during said transfer, and means for depositing a filler in said container to prevent damage of said material when packed.
- 20 23. An automatic container filling machine, comprising means for conveying open containers at intervals to a given point to be filled, means for supplying material for said containers, an intermittent reciprocating and rotating cross-head for transfer of said material from said supply to a container, suction means cooperating with said cross-head for picking a quantity of material up from said supply, means for breaking said suction for deposit of the same in a container, means for bringing a wrapping portion into association with said material during said transfer, means for depositing a filler in said container to prevent damage of said material when packed, and means for closing said containers.
- 25 24. An automatic container filling machine, comprising means for conveying open containers at intervals to a given point to be filled, means for supplying material for said containers, an intermittent reciprocating and rotating cross-head for transfer of said material from said supply to a container, a source of suction cooperating with said cross-head for picking up a quantity of material from said supply and depositing the same in a container, means for placing a wrapping portion in association with said material, and means for controlling said suction to deposit said material together with said wrapping portion in said container.
- 30 25. In an automatic container filling machine, the combination of means for conveying open containers to a given point to be filled, means for supplying material for said containers, said supply means including reciprocating means for holding unit quantities of material from said supply, reciprocating means for carrying said unit quantities of material thereon in spaced relation, and means associated therewith for simultaneously bringing a quantity of material from said supply into and holding the same in association with said reciprocating means and depositing a quantity of material previously brought into association with and held by said reciprocating means by a preceding reciprocation of said means in a container, the movement of said first-named reciprocating means being toward said second-named reciprocating means during transfer of said unit quantities of material thereto.
- 35 26. In an automatic container filling machine, the combination of means for conveying open containers to a given point to be filled, means for supplying material for said containers, reciprocating means having suction means associated therewith for carrying given quantities of material thereon in spaced relation, said means having intermittent rotary movement between the reciprocations, and means for controlling said suction means whereby said reciprocating means is adapted to pick up a quantity of material from said supply and deposit a quantity of previously picked up material by a preceding reciprocation of said means in a container.
- 40 27. In an automatic container filling machine, the combination of means for conveying open containers to a given point to be filled, means for supplying material for said containers, reciprocating means for carrying given quantities of material thereon in spaced relation, means for supplying wrapping portions for said quantities of material, means operable when said reciprocating means is in a certain position for bringing a quantity of material from said supply into and holding the same in association with said reciprocating means, means simultaneously operable for bringing a wrapping portion into association with another quantity of material brought into association with and carried by said reciprocating means by a preceding reciprocation of said means, and means simultaneously operable for depositing another quantity of material with its associated wrapping portion into a container, said last-named material having been brought into association therewith by a reciprocation of said means preceding said last-named reciprocation.
- 45 28. In an automatic container filling machine, the combination of means for conveying open containers to a given point to be filled, means for supplying material for said containers, reciprocating means having suction means associated therewith for carrying given quantities of material thereon in spaced relation, means for supplying wrapping portions for said quantities of material, said suction means having means for bringing a quantity of material from said supply into and holding the same in association with said reciprocating means, means for bringing a wrapping portion into association with another quantity of material carried by said reciprocating means, and means for depositing

another quantity of material with its associated wrapping portion into a container, said quantities of material having been brought into association with said reciprocating means successively.

29. In an automatic container filling machine, the combination of a cross-head, means for reciprocating said crosshead to effect movement of translation thereof, means for rotating said

10 cross-head material handling means associated with said cross-head, a second cross-head associated with said first cross-head for controlling said handling means, and means for reciprocating said second cross-head.

15 30. In an automatic container filling machine, the combination of a cross-head, drive means for reciprocating said cross-head to effect movement of translation thereof and means for rotating the same, material handling means associated with 20 said cross-head, a second cross-head associated with said first-named cross-head for controlling said handling means, and means operated by said drive means for reciprocating said second-named cross-head.

25 31. In an automatic container filling machine, the combination of a cross-head, means for intermittently reciprocating said cross-head to effect movement of translation thereof and holding the same momentarily when reciprocated, means for intermittently rotating said cross-head when the same is momentarily held in one of 30 said reciprocated positions, a second cross-head associated with said first-named cross-head, and means for reciprocating said second-named cross-

35 head when said first-named cross-head is at rest. 32. In an automatic container filling machine, the combination of a cross-head, drive means for reciprocating and rotating said cross-head to effect movement of translation thereof and means for 40 rotating the same, a second cross-head associated with said first-named cross-head, and means operated by said drive means for reciprocating said second-named cross-head when said first-named cross-head is at rest.

45 33. In an automatic container filling machine, the combination of a conveyor means, a cross-head associated therewith, drive means for said conveyor means and cross-head, said means including means for simultaneously and intermittently rotating said cross-head and conveyor means, means for reciprocating said cross-head to effect movement of translation thereof, a second cross-head associated with said first-named cross-head, and means for reciprocating said second-named cross-head when said first-named cross-head is at rest.

50 34. In an automatic container filling machine, the combination of a conveyor means, a cross-head associated therewith, drive means for said conveyor means and cross-head, said means including means for simultaneously and intermittently rotating said cross-head and conveyor means, means for reciprocating said cross-head to effect movement of translation thereof, a second cross-head associated with said first-named cross-head, and means operated by said drive means for reciprocating said second-named cross-head when said first-named cross-head is at rest.

55 35. In an automatic container filling machine, the combination of a conveyor means, a cross-head associated therewith, drive means for said conveyor means and cross-head, said means including means for intermittently rotating said conveyor means, means for reciprocating said cross-head to effect movement of translation

thereof, said conveyor means having means for intermittently rotating said cross-head therewith when the same is in a reciprocated position, a second cross-head associated with said first-named cross-head, and means for reciprocating said second-named cross-head when said first-named cross-head is at rest. 5

36. In an automatic container filling machine, the combination of a conveyor means, a cross-head associated therewith, drive means for said conveyor means and cross-head, said means including means for intermittently rotating said conveyor means, means for reciprocating said cross-head to effect movement of translation thereof, said conveyor means having means for 10 intermittently rotating said cross-head therewith when the same is in a reciprocated position, a second cross-head associated with said first-named cross-head, and means operated by said drive means for reciprocating said second-named cross-head 15 when said first-named cross-head is at rest.

37. In an automatic container filling machine, the combination of a continuously operated drive member, a cross-head having a member associated with said drive member, means associated with 25 said members for intermittently reciprocating said cross-head to effect movement of translation thereof, a second cross-head associated with said first cross-head, and means operated by said drive member for reciprocating said second cross-head 30 alternately with said first-named cross-head.

38. In an automatic container filling machine, the combination of a continuously operated drive member, a cross-head having a member associated with said drive member, cam means between said members for intermittently reciprocating said cross-head to effect movement of translation thereof, a second cross-head associated with said first cross-head, and means operated by said drive member for reciprocating 40 said second cross-head alternately with said first-named cross-head.

39. In an automatic container filling machine, the combination of a continuously operated drive member, a cross-head having a member associated with said drive member, means associated with said members for intermittently reciprocating said cross-head to effect movement of translation thereof, a second cross-head associated with said first cross-head, said drive member having a cam groove, and means movable in said groove for reciprocating said second cross-head alternately with said first-named cross-head. 45

40. In an automatic container filling machine, the combination of a continuously operated drive member, a cross-head having a member associated with said drive member, cam means between said members for intermittently reciprocating said cross-head to effect movement of translation thereof, a second cross-head associated with said first cross-head, said drive member having a cam groove, and means movable in said groove for reciprocating said second cross-head alternately with said first-named cross-head. 55

41. In an automatic container filling machine, the combination of a conveyor member having a plurality of depressed container receiving portions adjacent the periphery thereof, a plurality of radially disposed and movable arms associated therewith each terminating adjacent a container receiving portion, and means for moving said arms. 60

42. In an automatic container filling machine, the combination of a conveyor member having a plurality of depressed container receiving por- 70

75

- tions adjacent the periphery thereof, a plurality of radially disposed and movable arms associated therewith each terminating adjacent a container receiving portion, a cam groove disposed adjacent 5 the other end of said arms, and means connected to said arms and operable in said cam groove for moving said arms.
43. In an automatic container filling machine, the combination of a conveyor member having a 10 plurality of container receiving portions adjacent the periphery thereof adapted to receive containers having a hinged cover, means on said member for holding said covers in a position to be moved into closed position, a plurality of radially disposed and movable arms associated with 15 said member each terminating adjacent a cover for said container, and means for moving said arms to close said covers and for discharging said containers from said conveyor member.
44. In an automatic container filling machine, the combination of a conveyor member having a 20 plurality of container receiving portions adjacent the periphery thereof adapted to receive containers having a hinged cover, means on said member for holding said covers in a position to be moved into closed position, a plurality of radially disposed and movable arms associated with said 25 member each terminating adjacent a cover for said container, a cam groove disposed adjacent the other end of said arms, and means connected to said arms and operable in said cam groove for moving said arms.
45. In an automatic container filling machine, the combination of a fixed sleeve having a duct, 30 a cross-head movably mounted on said sleeve and having suction heads disposed in spaced relation, ducts leading from the duct in said sleeve and communicating with said suction heads, a member disposed in the duct of said sleeve, said member having an end movably journaled in said sleeve and its other end movably journaled in said cross-head, and a second cross-head mounted on said last-named end in association with said first-named cross-head.
46. In an automatic container filling machine, the combination of a cross-head having a plurality of ducts terminating in suction heads for picking up quantities of material and discharging the same, valve means disposed in said suction 40 heads for controlling the suction therein, reciprocating means for moving said valves, means for locking said valve in a position to break said suction, said reciprocating means operating said locking means to release said valves.
47. In an automatic container filling machine, the combination of a cross-head having a plurality of ducts terminating in suction heads for picking up quantities of material and discharging the same, valve means disposed in said suction 50 heads for controlling the suction therein, a second cross-head having means for moving said valves, and means for locking said valves in a position to break said suction.
48. In an automatic container filling machine, the combination of a cross-head having a plurality of ducts terminating in suction heads, valve means disposed in said suction heads for controlling the suction therein, a second cross-head having means for moving said valves, means for locking said valves in a position to break said suction, said second cross-head having means for operating said locking means to release said valves.
49. In an automatic container filling machine, the combination of means for transferring quantities of material, means for supplying wrapping 55 material, means for severing wrapping portions from said supply, and means for bringing wrapping portions of material into association with the material of said transfer means, said last-named means including a movable cutter of 60 said severing means and suction means associated with said transfer means.
50. In an automatic container filling machine, the combination of means for supplying wrapping portions of material, means for transferring given 65 quantities of material at intervals into spaced relation with a wrapping portion, means for moving said given quantities of material into association with said wrapping portions, and means holding said wrapping portion and quantities of material in association during subsequent movement of said transfer means.
51. In an automatic container filling machine, the combination of means for supplying wrapping portions of material, means for transferring given 70 quantities of material at intervals into spaced relation with a wrapping portion, means for moving said given quantities of material into association with said wrapping portions, and suction means for drawing a wrapping portion into 75 and holding the same in association with a given quantity of material during subsequent movement of said transfer means.
52. In an automatic container filling machine, the combination of means for supplying wrapping portions of material, means for transferring given 80 quantities of material at intervals into spaced relation with a wrapping portion, suction means for holding said quantities of material in association with said transfer means, means for moving said given quantities of material into association with said wrapping portions, said suction means serving to draw a wrapping portion into 85 and to hold the same in association with a given quantity of material during subsequent movement of said transfer means.
53. In an automatic container filling machine, the combination of means for supplying wrapping material, means for severing wrapping portions from said supply, means for transferring given 90 quantities of material at intervals into spaced relation with a wrapping portion, means for moving said given quantities of material into association with said wrapping portions, and suction means for drawing a wrapping portion into 95 and holding the same in association with a given quantity of material during subsequent movement of said transfer means.
54. In an automatic container filling machine, the combination of means for supplying wrapping material, means for severing wrapping portions from said supply, means for transferring given 100 quantities of material at intervals into spaced relation with a wrapping portion, suction means for holding said quantities of material in association with said transfer means, means for moving said given quantities of material into association with said wrapping portions, said suction means serving to draw a wrapping portion into 105 and to hold the same in association with a given quantity of material during subsequent movement of said transfer means.
55. In an automatic container filling machine, the combination of means for supplying wrapping material, means for feeding said supply to provide wrapping portions, a cross-head provided with suction means adapted to transfer given 110 quantities of material at intervals into spaced relation with a wrapping portion, means for severing said wrapping portions from said sup- 115

ply, means for moving said cross-head into a position to receive a wrapping portion, means operable when said cross-head is in said associated position for operating said severing means, 5 and means cooperating with said suction means for bringing said wrapping portion into association with said given quantity of material.

56. In an automatic container filling machine, the combination of means for supplying wrapping material, means for feeding said supply to provide 10 wrapping portions, a cross-head provided with suction means adapted to transfer given quantities of material at intervals into spaced relation with a wrapping portion, means for severing 15 said wrapping portions from said supply, means for moving said cross-head into a position to receive a wrapping portion, a second cross-head operable when said first-named cross-head is in said associated position for operating said severing 20 means, and means cooperating with said suction means for bringing said wrapping portion into association with said given quantity of material.

57. In an automatic container filling machine, the combination of means for supplying wrapping material, means for feeding said supply to provide 25 wrapping portions, a cross-head provided with suction means adapted to transfer given quantities of material at intervals into spaced relation 30 and adjacent one end of a wrapping portion, means for severing said wrapping portion from said supply, said means including a knife element disposed adjacent the other end of said wrapping portion, means for bringing a given quantity of 35 material into association with a wrapping portion, means operable when said cross-head is in said associated position for moving said knife element, said suction means serving to draw said first-named end of a wrapping portion into association 40 with said given quantity of material, means for moving said second-named end of said wrapping portion into substantial normal relation to the first-named end thereof, and means for holding said wrapping portion in said position.

45 58. In an automatic container filling machine, the combination of means for supplying wrapping material, means for feeding said supply to provide 50 wrapping portions, a cross-head provided with suction means adapted to transfer given quantities of material at intervals into spaced relation and adjacent one end of a wrapping portion, means for severing said wrapping portion from said supply, said means including a knife element disposed adjacent the other end of said 55 wrapping portion, means for bringing a given quantity of material into association with a wrapping portion, means operable when said cross-head is in said associated position for moving said knife element, said suction means serving to draw said first-named end of a wrapping portion into association with said given quantity of material, and means for moving said second-named end of said wrapping portion into substantial normal relation to the first-named end thereof, said suction means being adapted to hold said wrapping portion in said position.

60 59. In an automatic container filling machine, the combination of means for supplying wrapping material, means for feeding said supply to provide 65 wrapping portions, a cross-head provided with suction means adapted to transfer given quantities of material at intervals into spaced relation and adjacent one end of a wrapping portion, means for severing said wrapping portion from said supply, said means including

a knife element disposed adjacent the other end of said wrapping portion, means for bringing a given quantity of material into association with a wrapping portion, a second cross-head operable when said first-named cross-head is in said associated position for moving said knife element, said suction means serving to draw said first-named end of a wrapping portion into association with said given quantity of material, means for moving said second-named end of said 10 wrapping portion into substantial normal relation to the first-named end thereof, and means for holding said wrapping portion in said position. 5

60. In an automatic container filling machine, the combination of means for supplying wrapping material, means for feeding said supply to provide 15 wrapping portions, a cross-head provided with suction means adapted to transfer given quantities of material at intervals into spaced 20 relation and adjacent one end of a wrapping portion, means for severing said wrapping portion from said supply, said means including a knife element disposed adjacent the other end of said wrapping portion, means for bringing a given 25 quantity of material into association with a wrapping portion, a second cross-head operable when said first-named cross-head is in said associated position for moving said knife element, said suction means serving to draw said first-named 30 end of a wrapping portion into association with said given quantity of material, and means for moving said second-named end of said wrapping portion into substantial normal relation to the first-named end thereof, said suction means being adapted to hold said wrapping portion in said position. 35

61. An automatic container filling machine, comprising means for conveying open containers at intervals to a given point to be filled, means 40 for supplying material for said containers, an intermittent reciprocating and rotating cross-head for transfer of said material from said supply to a container, a source of suction cooperating with said cross-head for picking up a quantity of 45 material from said supply and depositing the same in a container, valve means carried by said cross-head and a second cross-head operating said valve means for control of said suction.

62. An automatic container filling machine, comprising means for conveying open containers at intervals to a given point to be filled, means 50 for supplying material for said containers, an intermittent reciprocating and rotating cross-head for transfer of said material from said supply to a container, a source of suction cooperating with said cross-head for picking up a quantity of 55 material from said supply and depositing the same in a container, valve means carried by said cross-head and a second reciprocating cross-head operating said valve means for control of said suction. 60

63. An automatic container filling machine, comprising means for conveying open containers at intervals to a given point to be filled, means 65 for supplying material for said containers, an intermittent reciprocating and rotating cross-head for transfer of said material from said supply to a container, a source of suction cooperating with said cross-head for picking up a quantity 70 of material from said supply and depositing the same in a container, means for controlling said suction, and means for bringing a wrapping portion into association with said material during said transfer. 75

cross-head for control of said suction, means for supplying wrapping material adjacent said material during said transfer, means controlled by said second cross-head for severing a wrapping portion for said material, means for bringing said wrapping portion into association with said material, and means associated with said conveying means for closing said container.

74. An automatic container filling machine, comprising means for conveying open containers at intervals to a given point to be filled, means for supplying material for said containers, an intermittent reciprocating and rotating cross-head for transfer of said material from said supply to a container, a source of suction cooperating with said cross-head for picking up a quantity of material from said supply and depositing the same in a container, a second reciprocating cross-head for control of said suction, means for supplying wrapping material adjacent said material during said transfer, means controlled by said second cross-head for severing a wrapping portion for said material, means for bringing said wrapping portion into association with said material, means associated with said second cross-head for depositing a filler in said container to prevent damage of said material when packed, and means associated with said conveying means for closing said container.

75. An automatic container filling machine, comprising means for conveying open containers at intervals to a given point to be filled, means for supplying material for said containers, said means including a platform, and means for transferring a quantity of material from said supply to said containers, said means including a cross-head, drive means for said cross-head, and means for intermittently rotating said conveying means and cross-head and reciprocating said cross-head for said transfer, said means including means for reciprocating said platform in opposite relation to the reciprocation of said cross-head.

76. An automatic container filling machine, comprising means for conveying open containers at intervals to a given point to be filled, means for supplying material for said containers, said means including a movable platform, and means for transferring a quantity of material from said supply to said containers, said means including a cross-head, drive means for said cross-head, and means for intermittently reciprocating and rotating said cross-head for said transfer, said reciprocating means including means for controlling the movement of the platform of said supply means.

77. An automatic container filling machine, comprising means for conveying open containers at intervals to a given point to be filled, means for supplying material for said containers, said means including a movable platform, and means for transferring a quantity of material from said supply to said containers, said means including a cross-head, drive means for said cross-head, means for intermittently reciprocating and rotating said cross-head for said transfer, said means including cam means for effecting said reciprocation, and means associated with said cam means for controlling the movement of the platform of said supply means.

78. In an automatic container filling machine, the combination of a drive member operated continuously in a single direction, a cross-head having a member associated with said drive member and rotated only in the direction of movement of said drive member, means associated with said members for intermittently reciprocating said cross-head, a second cross-head associated with said first cross-head, and means operated by said drive member for reciprocating said second cross-head alternately with said first-named cross-head.

EDWIN F. HULBERT. 40
